UNITED STATES PATENT OFFICE.

BRUCE W. TRAYLOR, OF NEW YORK, N. Y., ASSIGNOR TO TRAYLOR ENGINEERING & MANUFACTURING COMPANY, A CORPORATION OF DELAWARE.

ORE-CRUSHER.

1,035,273.

Specification of Letters Patent. Patented Aug. 13, 1912.

Application filed November 23, 1911. Serial No. 661,888.

To all whom it may concern:

Be it known that I, BRUCE W. TRAYLOR, a citizen of the United States, residing at New York, N. Y., have invented certain new and useful Improvements in Ore-Crushers, of which the following is a specification.

My present invention relates to an improved crusher for crushing ore and other hard materials and has for its object to provide a crusher having a centrifugal ore feed and at the same time a direct or reciprocating action as distinguished from the gyratory or rotary action of crushers as heretofore devised with a centrifugal feed.

Other objects are to provide a crusher of this type having multiple crushing jaws, and also to provide various novel features of construction with a view to producing a crusher of great efficiency, durability and economy.

With these and other objects in view the invention includes the various novel features and combinations of parts as defined by the appended claims.

A crusher constructed in accordance with my invention is illustrated in the accompanying drawings in which:

Figure 1 is a plan view of the crusher, Fig. 2 is a section on line 2—2 of Fig. 1, and Fig. 3 is a view partly in section, and partly in elevation.

Referring by reference characters to these drawings, the numeral 1 designates a feed hopper from which the material to be crushed is fed by gravity into the hollow screw conveyer which is in the form of a sleeve 2 provided with a spiral rib or ribs 2^a, the sleeve being removably held in the bearing member 3^a hereinafter more particularly described. Through this hollow spiral conveyer the ore is fed to the space between the two rotating heads 3 and 4 which carry the coacting crushing members or surfaces to which the ore is supplied by the centrifugal action produced by the rotation of the heads. The heads 3 and 4 are rigidly connected together at their outer edges by means of tubular spacing members 5 and bolts 6 and they are provided with oppositely extending tubular bearing members or sleeves 3^a and 4^a respectively, journaled in suitable bearings in portions 7^a and 7^b of the main frame 7. I secure the centrifugal action referred to by providing a bevel gear 8 fast on the end of member or sleeve

4^a with which meshes a bevel gear 8^a on a transverse shaft 9 carrying a pulley or other means by which power may be transmitted from any suitable source. To avoid end thrust due to the action of the bevel gears, I provide the bearing member 4^a with an annular flange 4^b and between this and the opposing surface of the bearing 7^b, I interpose bearing rings, one or more of which may be floating rings. In order to exclude dust from the bearing the parts 4^a and 7^b near the head 4 may be provided with circumferential interlocking ribs and grooves as indicated at 10. In order to secure the crushing action I provide the annularly arranged opposing crusher plates 11 and 12, preferably of manganese, the former being secured to the face of the inclined portion of the head or member 3, and the latter being secured to the carrier plates 13 which are movable toward and from the plates 11. The connection of the crushing plates may be conveniently effected by means of bolts 11^a and 12^a having countersunk heads. The carrier plates 13 have their outer edges in pivotal engagement with the head 4 near the outer edge thereof while their inner ends or edges have a pivoted engagement with a collar or flanged head 14^a which head is carried by a longitudinally movable shaft 14, the endwise movement of which rocks the carrier plates on their outer bearings, causing the crushing plates 12 to advance toward and recede from the plates 11 to crush the ore which has been supplied between the plates by the centrifugal action.

I have found a very advantageous form of pivotal connection to be that shown in the drawings in which the outer ends of the carrier members are provided with rounded projections or ribs 12^b resting in corresponding rounded recesses in wear plates 4^c carried by the head or member 4; the inner edges or ends of the carrier plates having similar rounded projections or ribs 12^d resting in recesses or grooves in the wear plates 4^c carried by the collar or flanged head 14^a.

The carrier plates are held in position by bolts 15 having T heads 15^a resting in recesses in the carrier plates, the bolts passing through openings in the head 4 and being supplied with compression springs 15^b, the pressure of which may be varied by means of the nuts and washers 15^c and 15^d. This construction not only enables ready removal

of the parts for renewal of worn crushing plates or like purposes, but provides at the same time, in a very simple and effective manner, for the reciprocation or oscillation 5 of the jaw plates, and holds them firmly in place in their bearings.

The longitudinal movement of the shaft 14 is effected through the medium of toggle links 16 and 17 and the interposed pitman 10 18 operated from an eccentric 19 on the transverse shaft 20 to which power is imparted from any convenient source. The toggle link 16 has one end in pivotal engagement with a cross head 21 guided in longitudinal ways 22 in the frame, the opposite end of the link being in pivotal engagement with the pitman. The other link has one end in pivotal engagement with the opposite side of the pitman and its other end in pivotal engagement with the frame of the machine as shown, the aforesaid pivotal connections being conveniently effected by providing the links with rounded ends engaging wear plates having correspondingly rounded recesses. The end of the shaft 14 seats rotatably against the cross head, the bearing being conveniently lubricated by an oil duct as shown, and in order to assist in bearing the crushing strain, I provide the end of 25 the shaft with a collar 14^x, between which and the cross head are interposed bearing rings 14^y, one or more of which may be floating rings.

The heads 3 and 4 rotate within a casing 30 23 which receives the pulverized ore or other material and from which said material may be removed in any convenient or desirable manner.

The upper halves of the bearing portion 40 7^a and 7^b are made removable for insertion and removal of the rotating parts and are provided with lubricating means as shown.

Having thus described my invention what I claim is:

45 1. In an apparatus of the class described a rotary element having an annular crushing surface, an opposing rotary element connected to said first named element to rotate in unison therewith, a plurality of annularly disposed plates carried by said second element and movable toward and from the crushing surface of the first named element as the elements rotate, and means for feeding ore between said crushing elements.

55 2. In an apparatus of the class described, a rotary element having an axial ore feed and annular crushing surface, an opposing rotary element connected with said first named element to rotate in unison therewith, a plurality of annularly disposed plates carried by said second element and movable toward and from the crushing surface of the first element and means for moving said plates as the elements rotate.

65 3. In an apparatus of the class described,

a rotary element having an axial ore feed and an annularly disposed ore crushing face, a second rotary element connected to rotate in unison therewith, a plurality of carrying plates having crushing surfaces 70 pivotally supported from said second element at their outer edges, and means for swinging the inner edges of said plates toward and from the crushing surface of the first named element as said elements rotate. 75

4. In an apparatus of the class described, a rotary element having a cylindrical bearing portion and an annular crushing surface, a spiral ore feeding device within said cylindrical portion, a second rotary element 80 spaced from and connected to said first named element to rotate in unison therewith, crushing means carried by said second element and movable toward and from the crushing surface of the first named element, 85 and means for moving said crushing means as said elements rotate.

5. In an apparatus of the class described, a rotary element having a hollow bearing portion and an inclined annular wall, a second rotary element spaced from and connected to first named element to rotate therewith, a plurality of annular arranged plates having their outer edges fulcrumed upon said second element, means for swinging 90 said plates toward and from the inclined surface of the first named element as said elements rotate, and means for feeding ore through the hollow portion of the first named element. 95

6. In an apparatus of the class described, a pair of rotary heads or elements having their outer edges spaced from and connected to each other, each of said heads having a cylindrical extension journaled in a suitable 105 support, and one of said heads having an annular crushing surface, means for feeding ore through the cylindrical extension of one of said heads, movable crushing devices carried by the other head, and means operating 110 through the cylindrical extension of the other head for moving said movable crushing devices.

7. In an apparatus of the class described, a rotary element having an axial ore feed 115 and an annularly disposed ore crushing face, a second rotary element connected to rotate in unison therewith, a tubular shaft supporting said second element, a plurality of carrying plates having crushing surfaces 120 pivotally supported from said second element at their outer edges, a second shaft longitudinally movable within said hollow shaft, a head on said shaft in operative engagement with the inner edges of said carrying plates, means for rotating said rotary elements, and means for reciprocating said second shaft. 125

8. In an apparatus of the class described, a rotary element having a cylindrical bear- 130

- ing portion and an annular crushing surface, a spiral ore feeding device within said cylindrical bearing portion, a second rotary element spaced from and connected to said 5 first named element to rotate in unison therewith, a tubular shaft supporting said second element, crushing means carried by said second element and movable toward and from the crushing surface of the first named 10 element, a second shaft longitudinally movable within said tubular shaft, means for rotating said tubular shaft, and toggle links for reciprocating said second shaft.
9. In an apparatus of the class described, 15 a rotary element having a hollow bearing portion and annular crushing surface, a second rotary element spaced from and connected to first named element to rotate therewith, a hollow shaft connected to said second element, a plurality of annular arranged plates having their outer edges fulcrumed upon said second element, yielding means connecting said plates with said second element, a second shaft within said hollow 20 shaft, a head on said shaft, in operative engagement with the inner ends of the plates, means for rotating said hollow shaft, means for reciprocating said second shaft and means for feeding ore through the hollow 25 portion of the first named element.
10. In an apparatus of the class described, 30 a pair of rotary heads or elements having their outer edges spaced from and connected to each other, each of said heads having a cylindrical extension journaled in a suitable 35

support, and one of said heads having an inclined crushing surface, means for feeding ore through the cylindrical extension of said head, plates having their outer edges fulcrumed on the second head near the outer 40 edge thereof, and means operative through the cylindrical extension of the second head for moving the inner edges of said plates.

11. In an apparatus of the class described, 45 a rotary head having a hollow bearing portion and annular crushing surface, means for feeding ore through said bearing portion, a second head peripherally connected to and spaced from said first named head, a hollow shaft carrying said second head, a 50 plurality of annularly arranged plates fulcrumed at their outer edges upon said second head, bolts having heads pivotally connected to said plates approximately centrally thereof, tension means connecting 55 said bolts with said head, a second shaft within said hollow shaft, a thrust member in engagement with the end of said shaft, toggle links engaging respectively said thrust member and a stationary part of the 60 machine frame, means for rotating said hollow shaft, and means for operating said toggle links.

In testimony whereof, I affix my signature in presence of two witnesses.

BRUCE W. TRAYLOR.
